United States Patent

Des. 242,388
Patented Nov. 16, 1976

242,388

THERAPEUTIC CUSHION

Jesse W. Castleberry, 442 N. Dillard St.,
Winter Garden, Fla. 32787

Filed May 29, 1974, Ser. No. 474,449

Term of patent 14 years

Int. Cl. D6—09; D24—99

U.S. Cl. D83—1 V

Fig. 1.

Fig. 2.

Fig. 3.

Fig. 4.

FIG. 1 is a perspective view of a therapeutic cushion showing my design;

FIG. 2 is a side elevation; the opposite side view being identical to the side elevation illustrated;

FIG. 3 is a front elevation; and

FIG. 4 is a rear elevation thereof.

I claim:

The ornamental design for a therapeutic cushion, shown and described.
